(57) **CLAIM**

The ornamental design for a beverage cup holder, as shown and described.

DESCRIPTION

FIG. 1 is a perspective view of a beverage cup holder showing my new design;

FIG. 2 is a top plan view thereof;

FIG. 3 is a side elevational view thereof; and,

FIG. 4 is a bottom plan view thereof.

All of the side elevational views are the same.

The broken-line showing of FIG. 1 illustrates a beverage cup and does not form part of the claimed design.
